FUEL INJECTION SYSTEM VENTING DEVICE

John F. Verkerke, Oak Park, Mich., assignor to General Motors Corporation, Detroit, Mich., a corporation of Delaware

Application August 1, 1957, Serial No. 675,767

4 Claims. (Cl. 261—37)

The present invention relates to a fuel reservoir venting mechanism for a fuel injection system and more particularly represents an improvement in the mechanism shown in copending application Serial No. 648,100 Olson et al.

It has been found advantageous in the subject type fuel injection system to maintain the fuel reservoir under a slight vacuum to draw off fuel vapors and thereby prevent the build-up of vapor pressures therein during idling operation under high ambient temperature operating conditions, particularly as encountered during the summer months or under conditions of reduced atmospheric pressure. Such high vapor pressures create an undesirable pressure on the fuel metering diaphragm tending to shift the latter in a direction increasing the fuel-air ratio causing the engine to eventually stall out due to over-enrichment. The provision of vacuum in the fuel reservoir prevents the vapor pressure build-up during idling under the conditions noted and is the subject of the aforesaid copending application.

It has been found, however, that the vacuum force introduced into the fuel reservoir is not only unnecessary but actually detrimental under certain ambient operating conditions. When the fuel vapor pressures are low, as during low ambient temperatures, the vacuum force in the reservoir, no longer necessary to neutralize vapor pressure, tends to shift the metering control diaphragm in a direction tending to lean the fuel-air mixture resulting in rough idling operation or stalling.

The present invention, therefore, provides a thermostatically controlled atmospheric vent in the fuel reservoir which will be opened when the ambient temperatures are relatively low thus eliminating the effect of any vacuum in the reservoir under conditions when it is unnecessary. On the other hand, the atmospheric vent is adapted to be closed when the ambient temperatures reach a level at which the formation of fuel vapors is likely to upset the normal functioning of the fuel metering valve.

The details of the present invention as well as other objects and advantages are set forth in the description which follows:

In the drawings:

Figure 1 is an elevational view of a fuel injection system embodying the subject invention;

Figure 2 is a partially sectioned enlargement of that portion of the system embodying the present invention;

Figure 3 is an enlarged view of the thermostatic vent valve; and

Figure 4 is a plan view of the thermostatic vent valve taken along line 4—4 of Figure 3.

The fuel injection system, per se, is shown and described in copending applications Serial No. 608,797 Olson, filed September 10, 1956 and Serial No. 608,853 Dolza, filed September 10, 1956 now Patent No. 2,843,098 dated July 15, 1958. Therefore, the system will only be described in such detail as is necessary to illustrate the present invention.

An air induction passage is shown at 10 and includes

2

a venturi portion 12 posteriorly of which is mounted a throttle valve 14 adapted to control the quantity of air flowing through the system. The air induction passage communicates with a plenum chamber 16 from which a series of ram pipes 18 communicate with the individual cylinders of the engine. Fuel is supplied to the individual ram pipes through nozzles 20. The individual fuel nozzles are supplied through passages 24 emanating from a fuel manifold or distributor 26 which is in turn supplied with fuel through a passage 28 leading from a metering device indicated generally at 30.

The fuel supplying and metering device 30, as shown in Figure 2, is mounted in a housing which includes a case 32 and a cover 34. A conduit 36 is formed in cover 34 and is supplied with fuel from a low pressure make-up pump, not shown. A float controlled valve mechanism 38 is also disposed in cover 34 and communicates with conduit 36 through a passage 40 to which filtered fuel is supplied in accordance with the vertical position of the valve member 38 as determined by the position of a pivoted float actuated arm 42. In the normal manner, as float arm 42 is raised and lowered the valve 38 will shut off or admit fuel into a fuel reservoir 44 provided in casing 32.

A constant displacement type pump 50 which is driven at engine speed is mounted in the fuel reservoir and is adapted to pump fuel from the reservoir 44 to a conduit 46 leading generally to a metering chamber 48.

A fuel metering mechanism is shown generally at 60 and includes a metering valve member 62 to which a diaphragm 64 is connected through a rod 66 and a lever 68 to meter the quantity of fuel supplied by said valve to conduit 28.

As best seen in Figure 2, the upper side of the diaphragm 64 is communicated through a passage 70 with the venturi 14 such that the position of the diaphragm is determined by the mass of air flow through the venturi as described in the aforesaid copending applications.

Chamber 48 is separated from the fuel reservoir 44 by a perforated partition 51. Inasmuch as wall 51 is perforated permitting communication between chambers 44 and 48, it is apparent that the pressure above the fuel level in these chambers will be the same and for present purposes the chambers may be regarded together as a large reservoir. Further, any pressure above the fuel level in chamber 48 will act on the upper end of the metering valve 62 as well as on the underside of diaphragm 64 through leakage around the control rod 66.

When the engine is idling under conditions of high ambient temperatures or low atmospheric pressures, as would be the latter case when operating in mountainous areas, vapor pressures build up within the chambers 44 and 48 to an extent causing the pressure force to act downwardly on the upper end of the metering valve 62 and upwardly on the diaphragm 64 both of which actions tend to increase the fuel supplied to conduit 28. The consequence of this added fuel is to over-enrich the idling mixture and thereby cause the engine to stall.

This situation has been eliminated in the device of copending application Serial No. 648,100 Olson et al. by providing a conduit 72 which communicates the one end with fuel reservoir 44 and at the other end with the fuel induction passage posteriorly of the throttle valve 14. In this way manifold vacuum will draw the fuel vapors out of the chambers 44 and 48 preventing the build-up of undesired pressures therewithin.

As set forth in the last mentioned copending application, full manifold vacuum is not admitted to the reservoir 44 through conduit 72 but rather means, such as an orifice, is provided in the conduit to reduce the vacu-

um force to a level which will just be sufficient to eliminate the vapor pressure problem encountered.

It has been found, however, under conditions of reduced ambient temperature or increased atmospheric pressure, the fuel vapor pressure in the reservoirs 44 and 48 is of a magnitude to create no fuel metering problem. On the other hand, under these same conditions the introduction of vacuum into reservoir 44 has the effect of itself disrupting the function of the metering valve 62 by tending to shift the diaphragm 64 downwardly which has the effect of leaning out the fuel-air mixture. To avoid this problem, an atmospheric vent port 80 is provided in reservoir cover 34. A thermostatically controlled valve 82 of a suitable bimetallic construction is mounted on the cover 34 and is adapted to coact with the vent 80 to uncover the vent when the ambient temperature is relatively low and to close the vent when the ambient temperatures reach a value at which the vapor pressure within the reservoir 44 again becomes troublesome. In this way, when the ambient conditions are such that vapor pressure within the reservoir 44 presents no problem, atmospheric vent 80 is open bleeding down the vacuum force in chamber 44. When the ambient temperature reaches a level at which the metering valve control is likely to be affected thereby, the thermostatic valve member 82 will close the atmospheric vent and the mechanism will function in the manner described in copending application Serial No. 648,100.

I claim:

1. A fuel injection system for an internal combustion engine comprising an air intake passage, a throttle valve for controlling flow through said passage, a fuel reservoir, conduit means communicating the reservoir with the individual cylinders of the engine, valve means disposed in said reservoir for controlling fuel flow to the conduit means, at least one end of said valve being exposed to the pressure in said reservoir above the fuel level, a pump for supplying fuel under pressure to said valve means, a pressure responsive member connected to said valve, a conduit connecting said member to the intake passage for controlling said valve in response to the quantity of air flowing through said passage, said diaphragm being exposed to the pressure in said reservoir above the fuel level, a conduit communicating the intake passage posteriorly of the throttle valve with the fuel reservoir to withdraw fuel vapors from the reservoir, and temperature controlled means for venting said reservoir to the atmosphere when ambient temperatures are below a predetermined value.

2. A fuel injection system for an internal combustion engine comprising an air intake passage, a throttle valve for controlling flow through said passage, a fuel reservoir, conduit means communicating the reservoir with the individual cylinders of the engine, valve means disposed in said reservoir for controlling fuel flow to the conduit means, a pump for supplying fuel under pressure to said valve means, a pressure responsive member connected to said valve, a conduit connecting said member to the intake passage for controlling said valve in response to the quantity of air flowing through said passage, means utilizing manifold vacuum for neutralizing the fuel vapor pressure in the reservoir, and a temperature responsive device for communicating said reservoir to the atmosphere to eliminate the effect of manifold vacuum in said reservoir when the ambient temperature is below a predetermined value.

3. A fuel injection system for an internal combustion engine comprising an air intake passage, a throttle valve for controlling flow through said passage, a fuel reservoir, conduit means communicating the reservoir with the individual cylinders of the engine, valve means disposed in said reservoir for controlling fuel flow to the conduit means, a pump for supplying fuel under pressure to said valve means, a pressure responsive member connected to said valve, a conduit connecting said member to the intake passage for controlling said valve in response to the quantity of air flowing through said passage, means utilizing manifold vacuum for neutralizing the fuel vapor pressure in the reservoir during relatively hot ambient operating conditions, a port communicating said reservoir to atmosphere, and a temperature responsive valve adapted to coact with said port to open the reservoir to atmospheric pressure during relatively cool ambient operating conditions.

4. A fuel injection system as set forth in claim 3 in which said temperature responsive valve comprises a bimetallic strip adapted to uncover said port when the ambient temperature is low and close said port when said temperature is high whereby pressure changes in said reservoir will have no effect on the actuation of said fuel control valve means.
